UNITED STATES PATENT OFFICE.

JOHN THOMAS SMITH, OF LANG BAY, BRITISH COLUMBIA, CANADA.

SKID-OILER.

1,356,794.

Specification of Letters Patent. Patented Oct. 26, 1920.

Application filed December 27, 1919. Serial No. 347,652.

To all whom it may concern:

Be it known that I, JOHN THOMAS SMITH, a subject of the King of Great Britain, and a resident of Lang Bay, in the Province 5 of British Columbia, Canada, have invented certain new and useful Improvements in Skid-Oilers, of which the following is a specification.

My invention relates to improvements in 10 devices for oiling the skids on which sleds employed in hauling shingle bolts travel, and the object of my invention is to provide a device for automatically oiling the skids in front of the sled so as to insure 15 its easy running, thus doing away with the necessity of applying the oil by hand labor as at present and effecting great economy in connection with the handling of shingle bolts.

20 I attain this object by the construction illustrated in the accompanying drawings in which—

Figure 1 is a side view showing the front 25 part of a sled with which my invention is embodied.

Fig. 2 is a front end view.

Similar figures of reference indicate similar parts in the views.

1 indicates generally the front portion of 30 a shingle bolt sled having the parallel side runners 2 and 3, while 4 indicates the skids on which the sled travels. At the present time it is customary for a man or boy to oil the skids in the path of the sled by 35 applying thick oil thereto by means of a brush, but this involves considerable expense for wages, and also for oil, since more oil is used than is actually necessary. In

order to overcome this defect I provide in the forward end of each runner a pipe 40 5 on the lower end of which is mounted a tubular collar 6 provided with a brush 7 adapted to contact with the skids as it is carried along by the sled, while the upper end of the pipe is provided with an oil 45 tank 8. The oil may be shut off from the pipe when required by any suitable type of valve.

The manner in which the device operates and its utility will be readily apparent, as 50 it will be seen that, the oil being turned on, it will flow down the pipe 5 into the brush 7 and be distributed on the skids in the path of the sled as the latter moves forward, so that the oiling operation is effected eco- 55 nomically and with great convenience.

What I claim as my invention is:—

1. The combination with a sled, of an oil feed pipe mounted vertically adjacent the front end of each sled runner, each 60 pipe being connected at its upper end with a tank and at its lower end with a downwardly directed brush disposed in front of its respective runner.

2. The combination with a sled, of a pipe 65 mounted vertically adjacent the front end of each sled runner, each said pipe being provided on its lower end with a tubular member having bristles adapted to brush over the sled track in front of its runners 70 and having on its upper end a tank for containing lubricant.

Dated at Powell River, B. C., this 20th day of November, 1919.

JOHN THOMAS SMITH.
